UNITED STATES PATENT OFFICE.

JOHN N. BELL, OF ONEIDA, NEW YORK.

TELEGRAPH-KEY.

1,127,855.

Specification of Letters Patent. Patented Feb. 9, 1915.

Application filed October 20, 1913. Serial No. 796,204.

To all whom it may concern:

Be it known that I, JOHN N. BELL, a citizen of the United States of America, residing at Oneida, in the county of Madison 5 and State of New York, have invented certain new and useful Improvements in Telegraph-Keys, of which the following is a specification.

This invention relates to telegraph keys 10 and more especially, to that form of telegraph key whereby a predetermined number of dots may be transmitted by one stroke of the key.

The objects of my invention are to provide a key of this character so constructed 15 as to be operated in the manner and with the same motions as now employed with the standard type of telegraph key; to provide a key of simple and cheap construction and 20 accurate in its operation.

With these, and such other objects in view, as may hereinafter more fully appear, my invention consists of the novel arrangements and construction of parts described 25 in the following specification and set forth in the claims, and which are shown in the accompanying drawings, wherein:—

Figure 1 is a plan view of the device. Fig. 2 is a side elevation. Fig. 3 is a vertical sectional view taken on the line A—A, 30 Fig. 1. Fig. 4 is a vertical sectional view taken on the line B—B Fig. 1. Fig. 5 is a detail view, partly in section, of the key levers and their support. Fig. 6 is a dia- 35 grammatic view of the circuit connections.

Referring to said drawings by numeral, a base 1, of a usual and ordinary type, has mounted thereon by means of a bolt 2 the support 3. Pivotedly mounted between the 40 upstanding arms of support 3, are the dash lever 4 which is in electrical contact with said support, and the dot lever 5, which is insulated from said support, preferably through a sleeve 6 of insulating material. The upward movement of levers 4 and 5 is restrained by a yoke 7 fastened to the end 45 of the base in any suitable manner and overlying said levers.

Pivotedly mounted in a bridge or sup- 50 port 8, which is suitably fastened to the base 1, is a lever arm 9 adapted to be contacted by the end of dot lever 5. Lever 9 is held in normal position by any suitable means, but preferably, by the coiled spring 10, 55 mounted in a suitable support 11 carried by the base 1, and adapted to contact with

one end of said lever. Resiliently mounted upon one end of lever 9, through the spring 12, is a vibrating bar 13. Bar 13 has slidably mounted thereon a weight 14 adjustably held in place by a screw 15. The position of said weight tending to regulate the vibratory motion of said bar 13. Bar 13 normally rests against the end of an adjusting screw 16 mounted in a threaded opening provided in a suitable support 17 carried by the base 1. The vibrating bar 13 is further provided with an adjustable collar 18 which has suitably fastened thereto the long arm of a hook shaped spring 19, the 60 end of the short arm of which is adapted to make contact with a terminal 20, carried by the base 1, when the arm 13 is vibrated. Bridge or support 8 has rigidly mounted thereon, crosswise thereof, a bar 21 which carries, by suitably threaded recesses, provided near the ends thereof, the adjusting screws 22, the ends of which contact with the ends of lever arm 9, and thereby limit the upward movements of said lever arm. 70

The operative ends of dash-lever 4 and dot lever 5 have mounted thereon the usual key 23, said key being divided vertically through the center thereof to permit of motion of said levers. Dash lever 4 is further 80 provided with an adjustable contact screw 24 adapted to engage a terminal 25 mounted on the base 1. The usual retracting spring 26 is also provided for said dash lever 4. The base 1 is also provided with 85 the usual terminal posts 27 and 28 and the switch 29.

The device is operated with the usual up and down stroke of the key 23, the half of the key attached to lever 4 being depressed 95 when it is desired to send a dash, and the half attached to lever 5 being depressed when sending dots. This gives the usual and ordinary position and motion heretofore assumed by an operator thereby doing 100 away with the necessity for learning a new movement, and allowing a perfect arm rest position so as to relieve all strain.

Having described my invention, what I claim as new and desire to secure by Letters Patent, is:—

1. A telegraph transmitter including a base having two main line terminals, a vertically swinging lever supported from the base and carrying a resilient "dot" contact 110 spring, a lever, a fixed "dash" contact carried by the lever, a second lever adapted to

operate said "dot" contact mechanism and a diametrically divided circular knob mounted on the operative ends of said levers.

- 5 2. A telegraph transmitter including a base supporting the line terminals, a horizontally pivoted "dot" lever carrying a resilient contact spring having a vertical movement, a "dash" lever and means for
10 operating said "dot" and "dash" lever,

said means comprising separate levers having at their outer ends, handles, each handle forming substantially half an ordinary circular key, substantially as described.

In testimony whereof I hereunto affix my 15
signature in presence of two witnesses.

JOHN N. BELL.
